DESIGN FOR A BOTTLE

Franz Neuschaefer, Rye, N. Y.

Application December 16, 1936, Serial No. 66,559

Term of patent 7 years

To all whom it may concern:

Be it known that I, Franz Neuschaefer, a citizen of the United States, and residing at Rye, in the county of Westchester and State of New York, have invented a new, original, and ornamental Design for a Bottle, of which the following is a specification, reference being had to the accompanying drawing, forming a part thereof:

Figure 1 is a front view of the bottle looking through the transparent front toward the rear which appears as a series of alternate contrasting vertical panels that form the dominating characteristic of my design.

I claim:

The ornamental design for a bottle, as shown and described.

FRANZ NEUSCHAEFER.
